UNITED STATES PATENT OFFICE

169,411

CHILD'S WALKER

Lloyd L. Becker, Burbank, Calif., assignor, by
direct and mesne assignments, to Clark &
Becker Toy Mfg., Burbank, Calif., a partnership

Application October 27, 1952, Serial No. 22,010

Term of patent 7 years

(Cl. D34—15)

To all whom it may concern:

Be it known that I, Lloyd L. Becker, a citizen of the United States, and a resident of Burbank, California, have invented a new, original, and ornamental Design for a Child's Walker, of which the following is a specification, reference being had to the accompanying drawing which forms a part of said specification and in which drawings:

Fig. 1 is a top plan view of a child's walker embodying my new design,

Fig. 2 is a side elevation,

Fig. 3 is a front end elevation, and

Fig. 4 is a rear end elevation.

I claim:

The ornamental design for a child's walker, substantially as shown.

LLOYD L. BECKER.
